UNITED STATES PATENT OFFICE.

WILLIAM R. PAYNE, OF POCAHONTAS, VIRGINIA, ASSIGNOR OF ONE-HALF
TO WILLIE W. JETER, OF SAME PLACE.

GUARD-RAIL BRACE.

SPECIFICATION forming part of Letters Patent No. 550,420, dated November 26, 1895.

Application filed September 30, 1895. Serial No. 564,183. (No model.)

To all whom it may concern:

Be it known that I, WILLIAM R. PAYNE, a citizen of the United States, residing at Pocahontas, in the county of Tazewell and State 5 of Virginia, have invented a new and useful Guard-Rail Brace, of which the following is a specification.

My invention relates to guard-rails, and particularly to the braces therefor, it being 10 my object to provide a rigid brace for the guard-rail used in connection with a siding-frog, by means of which the guard-rail is secured from spreading.

My improved brace is to be placed one half 15 thereof on the inside of the middle portion of the guard-rail opposite the frog-point and the other half opposite thereto on the outside of the adjacent main rail or siding-rail, as the case may be, and the two halves are then 20 firmly bolted together through and beneath the intervening rails.

My invention consists in the details of construction and combinations of parts hereinafter described and claimed.

25 In the drawings, Figure 1 is a plan view of my invention in operative adjustment. Fig. 2 is a side elevation thereof. Fig. 3 is a vertical cross-section adjacent to the clamping-blocks, and Fig. 4 is a similar view adjacent 30 to the bracing-legs.

Reference-numeral 1 designates the guard-rail and 2 designates the line-rail in their ordinary adjustment adjacent to a switch. These are ordinarily spiked in position or the 35 guard-rail is sometimes provided with lateral struts or braces on its inner side. In my construction a head-plate or bar 3, about fourteen inches long, is provided to rest in facial contact against the web of the rail and about 40 under the rail-head and on the flange. Accordingly, plate 3 is formed with a vertical inner side 4 and top 5 and bottom 6, slightly divergent from each other and extending obliquely from side 4. The outer side 7 slopes 45 outwardly, so as to form a thickened support 6 substantially the width of the rail-flange.

At either end plate 3 is provided with a laterally-extending and outwardly-flared knee or strut brace 8. This knee 8 is substantially 50 flush at its inner end with the upper edge of plate 3 and slopes downwardly toward its outer

end, where it is flanged horizontally to provide the extended foot 9. Foot 9 is peripherally notched at 10 to receive the fastening-spikes. These notches are so arranged that 55 when the brace is properly adjusted on the ties the spikes will be out of alignment with the grain of the wood, so as not to split the ties. Intermediately of said knees 8 clamping-block 12 is provided, extending vertically 60 along the middle of the outer face 7 of the head-plate and projecting therebelow to form a bolt-flange 13, suitably perforated to receive clamping-bolt 14. Said block is also provided in its upper portion with another 65 perforation 15 for bolt 16 to enter in vertical alignment with bolt 14. This block conforms to the sloping sides 7 of plate 3 and is substantially rectangular in front elevation, with truncated corners 17, and has its outward face 70 18 sloped inwardly slightly from the top toward the lower end 13.

In use a brace-piece, as above described, is fitted against the inner side of the guard-rail 1, and a similar brace-piece is fitted against 75 the outer side of rail 2, with their head-plates 3 rested against the respective webs and flanges of said rails and with their bolt-holes in alignment with each other and with corresponding bolt-holes through the webs of the 80 rails. Bolt 16 is then threaded through the near clamping-block, rail-webs, and farther clamping-block and secured by nut 19 on its threaded end. Square bolt-holes are formed in the outer piece to receive the squared 85 shanks 20 of the bolt-heads, so as to prevent the same from turning. A filling-block 21, with converging ends 22 to fit snugly, is also provided between the clamping-flanges 13 and lies closely against the bottom of the rail 90 and is suitably perforated. This is adjusted in place between said converging flanges, and bolt 14 is threaded through said flanges and filling-block and secured by nut 23. Spikes are now driven through the various notches 95 10 into the ties, and the entire brace-chair is thereby adjusted.

It is evident that the line-rail and guard-rail must remain in their relative positions when my brace is used, for whatever lateral 100 thrust is brought on the guard-rail by a wheel-flange is distributed by means of the head-

plate to the knees, which are of a stocky powerful shape, and through them to the ties, and also by said head-plate to the clamping-block, whose thick upper end bears the shock 5 and conveys the same by means of bolt 16 to the opposite brace-piece and whose flanged lower end transmits the strain also to the opposite brace-piece by means of the filling-block and bolt 14, so that the two rails are rigidly secured together and also rigidly braced in position on the ties.

What I claim is—

1. A brace piece for a guard rail, consisting of a head plate adapted to rest against and be secured to the inner face of a guard rail and provided at either end with an outwardly flaring knee having a horizontally flanged foot notched on its edges to receive fastening spikes, and a block secured to said head plate 15 midway between said knees and having a thicker upper portion and a thinner lower portion or flange perforated and extending below said head plate, substantially as described.
2. A guard rail brace consisting of two bolts and two brace pieces, each of said brace pieces comprising a longitudinal head plate shaped to conform to the adjacent face of the rail and provided at either end with an 20 outwardly flaring knee having a horizontally flanged foot suitably notched to receive fastening spikes, and a clamping block arranged in the outer side of said head plate midway between said knees and extending vertically 25 down below said head plate, and horizontal perforations one through the middle of said

head plate and block and one through said extension, all arranged and combined, substantially as described.

3. The combination with a line rail and a 40 guard rail, of a brace piece arranged adjacent the inner side of said guard rail and having a head plate shaped to conform to the web and continuous portions of the head and flange of said rail, said head plate being provided at either end with an outwardly flaring knee adapted to be spiked to the tie and also provided midway between said knees with a vertical clamping block thick at its upper end and provided with a flange of less thickness 45 extending below and underneath the rail bottom, and a second and similar brace piece arranged adjacent the outer side of said line rail, a wedge shaped filling block arranged to abut against the rail bottom and between 50 the converging flanges of the clamping blocks, and two bolts, one passing through suitable perforations therefor in the clamping blocks, head plates and rails and the other passing through suitable perforations in the clamping 55 block flanges and filling block whereby said rails are bolted together in their proper adjustment and laterally braced, substantially as described.

In testimony that I claim the foregoing as 60 my own I have hereto affixed my signature in the presence of two witnesses.

WILLIAM R. PAYNE.
